UNITED STATES PATENT OFFICE

151,113

DESIGN FOR A TOASTER

Paul Yaeger, New York, N. Y., assignor to Valiant Appliances, Inc., New York, N. Y., a corporation of New York

Application August 6, 1947, Serial No. 140,737

Term of patent 14 years

(Cl. D81—10)

To all whom it may concern:

Be it known that I, Paul Yaeger, a citizen of the United States of America and resident of the city, county, and State of New York, have invented a new, original, and ornamental Design for a Toaster, of which the following is a specification, reference being had to the accompanying drawing, forming a part thereof, in which:

Fig. 1 is a perspective view of the top, one end and one side of a toaster embodying my new design; and

Fig. 2 is a perspective view of the top, the other end and other side thereof.

I claim:

The ornamental design for a toaster, as shown.
PAUL YAEGER.
